CLAIM

The ornamental design for a storage and retrieval carousel drawer, as shown and described.

DESCRIPTION

FIG. 1 is a perspective view of a storage and retrieval carousel drawer, showing our new design;

FIG. 2 is a front elevational view thereof;

FIG. 3 is a rear elevational view thereof;

FIG. 4 is a right-side elevational view thereof, the left-side elevational view being the mirror image thereof;

FIG. 5 is a top plan view thereof; and,

FIG. 6 is a bottom plan view thereof.

FIG. 2

FIG. 3

FIG. 4FIG. 5

FIG. 6
